LOUIS MARX, OF BROOKLYN, NEW YORK.

TOY ROUNDABOUT.

Application filed April 10, 1925. Serial No. 22,015.

This invention relates to toys, and more particularly to mechanically operated toys; and has special reference to the provision of a mechanically operated toy of the type in which a toy figure may be actuated to travel in a circular orbit or path for simulating any of a variety of actions such as a cycle or automobile race and the like.

Mechanically operated toys of the type referred to are now well known, and generally comprise a platform formed of a central disk-like member and an annular member surrounding the same, the annular space between the members defining a circular orbit or path in which the operated figure or figures is or are adapted to travel, such figures being connected by means concealed by said platform to a motor which is usually arranged centrally of said platform. In these constructions the annular member is employed to support the central disk-like member so as to space the same from a supporting plane to permit unhindered operation of the motor mechanism, and the said annular member is connected to the central platform member by various means such as a plurality of arch-shaped members.

The manufacture of these mechanically operated toys is accompanied by a number of difficulties resulting from and incident to the manner in which the various members are assembled in accordance with the principles heretofore practiced. To obtain a more or less rugged construction, the annular member surrounding the central platform member must be connected thereto in a rigid manner so that all the parts may be held in mutually supported relation, and where the toy is assembled automatically and manufactured by quantity production methods, it is a matter of great difficulty to obtain a structure which will withstand moderately rough usage. Moreover, because of the inherent construction of the toy, the movable toy figures travel within the annular space and do not impart that close simulation to the imitated action which is most desired. Furthermore, the number of parts of the toy is comparatively large for the action desired to be produced, and the cost of the number of dies employed in the manufacture of the toy, as well as the cost of assembling the parts, is reflected in the increased selling price of the assembled toy.

A prime desideratum of my present invention, therefore, comprehends the provi-

sion of an improved toy of the character referred to, in which these disadvantages in construction, mode of manufacture and operation of the toy are effectively eliminated, the invention comprehending more specifically the provision of an improved mechanically operated toy of this type in which the annular member and the supporting means therefor are eliminated, and in which the movable toy figure is related or associated with the stationary platform in a way to effect a very close simulation of the action which is desired to be imitated. As the description of the invention proceeds, it will be apparent to those skilled in the art that by means of my improvements, the number of parts of the toy are reduced, with a consequent reduction in the number of dies employed, and the remaining parts of the toy are so inter-related or associated as to produce a strong, rugged and durable toy which may be manufactured and sold at comparatively low cost.

To the accomplishment of the foregoing and such other objects as may hereinafter appear, my invention consists in the elements and their relation one to the other, as hereinafter particularly described and sought to be defined in the claims; reference being had to the accompanying drawings which show preferred embodiments of my invention, and in which:

Fig. 1 is an elevational view with parts shown in section of my invention showing the same in one embodiment thereof,

Fig. 2 is a plan view thereof with parts broken away,

Fig. 3 is an elevational view with parts broken away showing another embodiment of the invention, and

Fig. 4 is a plan view of the same with parts broken away.

Referring now more in detail to the drawings, and having particular reference first to Figures 1 and 2 thereof, the improved toy embodying the principles of my invention comprises a circular platform 10 defining a stage upon which the desired action is to be produced, the said platform being provided with a centrally arranged motor 11 which is encased in or contained by a motor housing 12. The platform 10 may be given any desired contour, depending upon the action to be simulated, and in the embodiment of the invention shown in Figs. 1 and 2, the platform is made disk-shaped

and is contoured to simulate a racing bowl over which a plurality of figures may be caused to travel. The platform 10 and the housing 12 are preferably made of sheet metal joined together in any approved fashion, and the walls of the housing 12 may, as will readily be understood, be decorated or ornamented in consonance with the action desired to be simulated, and as shown in Fig. 1 of the drawings, the same may represent a grand stand and the spectators therein.

The motor 11 may comprise any suitable construction well known to those skilled in the art, and for purposes of illustration is shown to consist of a spring motor 13 supported on a bracket 14, which latter is fixed to the platform 10, the said spring motor being connected at its opposite ends to a stop ratchet 15 and a gear 16, the gear being fixed to a drum or cylinder 17 which is unitary with a winding shaft 18, said shaft being adapted to receive a winding key for energizing the motor. The gear 16 is connected by means of a simple gear train generally designated as 19 to a central driven shaft 20, which shaft projects through the platform 10 for connection to the operated members, as will be described presently. It will be apparent that when the spring motor is energized, the shaft 20 will be rotated to impart motion to the members connected thereto.

In the embodiment shown in Figs. 1 and 2 of the drawings, a cycle race is simulated, and to this end a plurality of toy cyclist figures 21, 22 and 23 are provided, which figures, preferably made of sheet metal, are arranged so as to be movable on or over the platform 10 in a circular orbit or path actuated by the rotation of the motor shaft or spindle 20, the said figures being connected to the said motor shaft by means of preferably radially arranged spider arms 24, 25 and 26 underlying the platform 10 and concealed thereby.

To effect a close simulation of the racing action, it is desirable that the moving toy figures 21, 22 and 23 be made to travel on or over the platform in a path or orbit spaced inwardly of the periphery or rim 10' of the platform, and to this end each of the spider arms forming the connecting means between the figures and the motor shaft extends underneath the platform from the drive shaft to the rim of the platform and then upwardly and inwardly about the rim of the platform to its associated toy figure, the spider arm 24 comprising, for example, a horizontal section 24' underlying the platform, a short vertical section 24², and a short inwardly directed horizontal section 24³ bent around the rim 10' of the platform 10, the section 24³ being fixed to the toy figure 21 and preferably in a manner to move the same without physically contacting the floor of

the platform. The other arms 25 and 26 are similarly constructed, and are designated by similar reference characters.

The platform 10 and its associated parts are supported in a suspended position so as to be spaced from a horizontal supporting surface 27 to permit free action of the motor and the figures connected thereto. To this end there is provided a plurality of supporting legs 28, 29 and 30 which may be connected either to the platform 10 or to the motor housing 12, the latter being shown in the drawings, the said legs being arch-shaped as shown and provided with foot portions such as 28' and 30' adapted to engage the supporting surface 27.

By means of this construction, it will be apparent that I am enabled to ruggedly associate the operated toy figures with the operating motor to produce a strong and durable toy, and that the parts of the toy may be effectively reduced without sacrificing the desired action or the manner of supporting the parts of the same.

Referring now to Figs. 3 and 4 of the drawings, I show another embodiment of the invention in which a train of cars is caused to travel in a given circular path in simulation of the movement of the train over the track rails. In this embodiment of the invention, the platform also comprises a disk-shaped member 30^a having centrally arranged thereon a motor housing 31 containing a motor (not shown), which motor has a winding shaft 32 and a centrally arranged driven spindle or shaft 33, the latter being connected to a toy train of cars 34 by means of a connecting member 35 extending underneath the platform from the drive shaft 33 to the rim of the platform, and then extending upwardly and inwardly about the rim of the platform to the train of cars 34 in a manner similar to that heretofore described. The motor housing 31 may be given a configuration and may be ornamented to simulate a railroad station, and the surface of the platform 30 may be decorated in consonance therewith, the same being provided with simulated track rails 36, 36 which may form part of the ornamentation.

For supporting the platform 30 and its associated parts, arch-shaped leg members 37, 38 and 39 may be provided similar to those heretofore described, these arch-shaped leg members being provided with foot portions such as 37' and 39' at their lower ends, and being connected at their upper ends to the motor housing 31. Desirably the arch-shaped leg members are contoured to simulate tunnels or bridges through which the train of cars is moved.

The manner of making and using the improved toy embodying the principles of my invention, and the advantages thereof, will

in the main be fully apparent from the above detailed description thereof. It will be further apparent that while I have shown my invention in the preferred embodiments, 5 many changes and modifications may be made in the structure disclosed without departing from the spirit of the invention, defined in the following claims.

I claim:

- 10 1. A mechanically operated toy comprising a circular platform having an outer free periphery or rim, a toy figure arranged to travel on said platform in a circular path or orbit spaced inwardly of the periphery 15 or rim of the platform, a motor carried by and arranged centrally of said platform, means connecting said motor with said figure for causing the figure to travel in its orbit when the motor is in an energized 20 state, said connecting means extending underneath the platform from the motor to the rim of the platform and then upwardly and inwardly about the rim of the platform to the toy figure, and means 25 for suspendedly supporting the platform and the parts carried thereby, the said last mentioned supporting means comprising a plurality of arch-shaped legs connected to the upper side of said platform.
- 30 2. A mechanically operated toy comprising a disk-shaped circular platform defining a track, a vehicle toy figure arranged to travel on said platform in a circular path or orbit, a motor housing and motor carried by and arranged centrally of said platform, means underlying said platform connecting the motor with said vehicle figure for causing the latter to travel in its orbit when the motor is in an energized state, and means 35 for suspendedly supporting the platform and its associated parts in a position elevated or 40 raised from a supporting surface,

the said supporting means comprising a plurality of arch-shaped legs fixed to said motor housing and contoured to simulate tunnels or the like. 45

3. A mechanically operated toy comprising a circular platform having an outer free periphery or rim, a toy figure arranged to travel on said platform in a circular path or orbit defined by the said outer free periphery or rim, a motor carried by and arranged centrally of said platform, an arm underneath said platform having a part bent about said periphery, said arm connecting said motor with said figure for causing the figure to travel in its orbit when the motor is in an energized state, and means for suspendedly supporting the platform and the parts carried thereby, said supporting means comprising a plurality of legs connected to the upper side of said platform and defining arches through which the figure travels. 55

4. A mechanically operated toy comprising a circular platform, a toy figure arranged to travel on said platform in a circular path or orbit, a motor carried by and arranged centrally of said platform, a motor housing for said motor, means connecting said motor with said figure for causing the figure to travel in its orbit when the motor is in an energized state, and means for suspendedly supporting the platform and its associated parts in a position elevated or 70 raised from a supporting surface, the said supporting means comprising a plurality of legs fixed to said motor housing and defining arch members through which the figure travels. 75

Signed at New York city, in the county of New York and State of New York, this 6th day of April, A. D. 1925.

LOUIS MARX.
